UNITED STATES PATENT OFFICE

2,101,767

CALCULATING MACHINE

Edward C. Walter, Orange, N. J., assignor to
 Monroe Calculating Machine Company, Orange, N. J., a corporation of Delaware

Application February 19, 1937, Serial No. 126,699

2 Claims. (Cl. 235—79)

The invention has relation to calculating machines, capable of making any number of cycles of continuous rotation and constructed in accord with the disclosure of the U. S. patent to A. A. 5 Overbury, issued June 26, 1934, No. 1,964,211, and other patents of the well-known Monroe type, having for an object the provision of improved means for locating the actuating mechanism of the machine at rest in full cycle position.

10 The invention consists in the novel construction and combinations of parts as hereinafter set forth in the claims.

In the accompanying drawing,

15 Figure 1 is a side view of the machine to which the invention is applied with parts broken away and parts removed.

Figure 2 is a view of the opposite side of the machine with parts broken away, showing the invention applied to one of the main operating 20 shafts of the machine.

Figure 3 is a similar view with the spring tensioned members moved outwardly and so held.

Figure 4 is a similar view showing the holding 25 means for said spring tensioned members released and said members moved inwardly to the cam.

In the drawing, and as more fully described in said patent, trigger 31 normally engages a pawl 25, mounted upon a stop arm 24, and serves to hold said pawl inactive, and on release of a general operation key (not shown) said trigger will be raised and pawl 25 released, the latter dropping into position behind a shoulder 27 of rock arm 22, connected to shaft 4 by crank 28 and link 30 21. This connects the arms 22 and 24 to move in unison, the latter arm being carried forwardly against a fixed stop 29 to prevent further operation of the parts in the original direction.

Upon the rebound of the parts from stop 29, 40 a lug of pawl 25 will engage with the end of trigger 31, and lift said pawl out of engagement with shoulder 27, the present invention providing improved means for locating the actuating mechanism at rest in full cycle position.

45 Upon the shaft 4 of the actuating mechanism for the numeral wheels etc., and which is one of the main operating shafts of the machine, is fixed a cam 1, having diametrically opposite low points 2, 2; arms or members 3, 3, pivoted in common at one end thereof at 5, being provided at their free ends each with a roller 6, and having a spring connection 7, and a toggle joint connection 8, said rollers normally engaging said low points of the cam.

50 On initial movement of the actuating mecha-

nism of the machine, said cam acts to move said members outwardly, and to move the links of said toggle joint connection outwardly towards centralized position, against the tension of said spring connection, said cam having a projection 9, 5 engaging said toggle joint connection to move the links thereof further outwardly through and slightly beyond centralized position, one of said links having a projection 10 engaging the adjacent of said members 3, 3, as seen in Figure 3, to hold said members so moved outwardly and said toggle joint connection in the position stated.

Means are provided operable after the actuating mechanism has passed through full cycle position to engage the projection of said link and move the links of the toggle joint connection in the opposite direction through and beyond centralized position, when the spring connection will act to move said members inwardly until the rollers thereof contact high points of said cam; and 10 on the rebound of the parts the rollers will ride down on the cam and seat in the low points thereof to locate the actuating mechanism at rest in full cycle position, said means being described as follows:

25 The stopping means of the machine has connection 11 to an arm 12, pivoted at 5, said connection being attached at one end thereof to the free end of said arm 24, and at the other end to the free end of said arm 12, and acting to move 30 the latter into contact with said projection 10. The arm 12 is operated as stated against the tension of its spring 13, said spring acting to return said connection and said arm to normal position. The connection 11 which may be of wire passes 35 transversely of the machine through apertures 14 of the sides of the machine casing in order that it may be attached at its ends as stated, and is guided and protected by engagement with the interior of a coiled spring 15, which also passes 40 through said apertures and is attached at its ends to brackets 16 fixed to the sides of said casing.

45 The release early in the cycle of operation of the machine of the toggle joint connection 8 and contact of the rollers of the arms or members 3, 3, with high points of the cam 1 is herein provided for, rather than later release of said toggle joint connection at the time that the low points of the cam are opposite said rollers, the 50 reason for this being that the cam itself cannot accomplish such release.

I claim:

.1. In a calculating machine having numeral wheels, actuating mechanism therefor, and stop- 55

ping means operable after the actuating mechanism has passed through full cycle position to retard said mechanism and to return the same to full cycle position; means for locating the actuating mechanism at rest in full cycle position including a cam having operating connection with said actuating mechanism and provided with opposite low points, spring tensioned members engaging said low points of the cam, said cam acting on initial movement of said actuating mechanism to move said members outwardly against the tension of their spring, means including a toggle joint for holding said members so moved outwardly, and means having operating connection with said stopping means and operable after the actuating mechanism has passed through full cycle position to release said holding means.

2. In a calculating machine having numeral wheels, actuating mechanism therefor, and stopping means operable after the actuating mechanism has passed through full cycle position to retard said mechanism and to return the same to full cycle position; means for locating the actu-

ating mechanism at rest in full cycle position including a cam having operating connection with said actuating mechanism and provided with opposite low points, members engaging said low points of the cam and having a spring connection and a toggle joint connection, said cam acting on initial movement of said actuating mechanism to move said members outwardly and the links of said toggle joint connection outwardly towards centralized position against the tension of said spring connection, said cam having a projection engaging said toggle joint connection to move the links thereof further outwardly slightly beyond centralized position, one of said links having a projection engaging the adjacent of said members to hold said members so moved outwardly, and means having operating connection with said stopping means and operable after the actuating mechanism has passed through full cycle position to engage said projection of said link and move said links inwardly beyond centralized position.

EDWARD C. WALTER.
